CLAIM

The ornamental design for a tight, as shown and described.

DESCRIPTION

FIG. 1 is a right, front perspective view of a tight according to the present design;

FIG. 2 is a right, front perspective view of the tight depicting a different configuration of use;

FIG. 3 is a front view thereof;

FIG. 4 is a right side view thereof;

FIG. 5 is a left side view thereof; and,

FIG. 6 is a back side view thereof.

The evenly spaced broken lines shown in the drawings illustrate environment, and form no part of the claimed design.

The dot-dash broken lines are boundary lines, which define the bounds of the claimed design. These boundaries do not exist in reality in the article embodying the design. It is understood that the claimed design extends to these boundaries but does not include the boundaries.

(Continued)

The depiction of the crosshatched portions of the garment reflects a generic mesh pattern spanning these parts of the garment.

1 Claim, 5 Drawing Sheets
